UNITED STATES PATENT OFFICE.

GEOERGE BOLTZ, OF DIGHTON, KANSAS.

ROTARY ENGINE.

1,151,562.

Specification of Letters Patent. Patented Aug. 31, 1915.

Application filed November 25, 1913. Serial No. 802,967.

To all whom it may concern:

Be it known that I, GEORGE BOLTZ, a citizen of the United States, residing at Dighton, in the county of Lane, State of Kansas, have invented certain new and useful Improvements in Rotary Engines; and I do hereby declare the following to be a full, clear, and exact description of the invention, such as will enable others skilled in the art to which it appertains to make and use the same.

This invention relates to engines and has special reference to an engine wherein the piston rotates continually in one direction and which is known as a rotary engine.

The principal object of the invention is to improve and simplify the general construction of devices of this character.

A second object of the invention is to provide an improved arrangement for the stator and rotor of certain engines.

A third object of the invention is to provide an improved means for controlling the steam supply of such an engine.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a side elevation of an engine constructed in accordance with this invention. Fig. 2 is a section on the line 2—2 of Fig. 1. Fig. 3 is a detail view showing the inside of one of the stator elements. Fig. 4 is a section on the line 4—4 of Fig. 2. Fig. 5 is a section through the rim of the engine showing the abutment. Fig. 6 is an enlarged detail view showing the valve arrangement, the valve being shown in section. Fig. 7 is a detail perspective view of the abutment. Figs. 8 and 9 are detail views in section through the valve showing the same open and closed.

In the present embodiment of this invention there is provided a base 10 whereon are carried supports 11. These supports are connected, as will be hereinafter described, to the stator of the engine and this stator consists of two symmetrical halves. Each of these halves consists of a substantially cylindrical body portion 12 having the hollow space 13 and flange 14. These two stator halves are secured together by bolts

15 so that when thus secured a steam space 16 is formed therein. Each half of the stator is provided with a centrally disposed opening 17 and in these openings is journaled a shaft 18. The shaft 18 has keyed thereto the rotor which consists of a hub portion 19, a flange portion 20 extending from the hub portion and a rim 21. In the stator halves are provided oppositely disposed annular grooves 22 while the sides of the rotor rim are similarly provided with grooves 23. The grooves 22 and 23 are, when the parts are assembled, in opposition so that in these grooves may be fitted the packing rings 24 which thus serve to render the space 16 outside of the rotor steam tight with respect to the spaces between the stator and flange portion 20 of the rotor. It is to be understood that the stator sides are provided with suitable wearing plates 25 and that the rotor sides are provided with similar wearing plates 26 so that these parts may be renewed after wear and also so that the rotor will fit tightly in the stator and thus prevent the waste of steam. The stator is supported by the supports 11 and is held from rotation in said support by means of suitable bolts 26'.

Extending upward from the base 10 are standards 27 which are provided at their upper ends with bearings 28. The shaft 18 passes through the bearings 28 and where it passes through these bearings is provided with frusto-conical portions 29 which are surrounded by bushings 30 which have frusto-conical inner surfaces adapted to fit the portions 29 of the shaft and cylindrical outer surfaces adapted to fit the bearings 28. These bushings are held in position in the bearings by means of suitable bolts or set screws 31 so that, in case of wear, it is simply necessary to loosen the said screws and force the bushings 30 into engagement with the shaft 18.

Formed upon the rotor is a piston 32 having slanting sides 33 for purposes hereinafter to be described. This piston 32 is of the same width as the rotor rim and the wear plates 26 of the rotor extend up along the sides of the piston to provide for the wear thereof. The inner sides of the stator halves are each provided with a radial groove 34, said grooves being oppositely disposed. In these grooves slides an abutment 35 having at its upper end a pair of spaced ears 36 between which is secured one end of

an arm 37 the upper end of which receives therethrough one end of a spring 37' constantly urging the abutment 35 inward. The grooves 34 extend inwardly of the portion of the stator occupied by the piston and the abutment 35 is provided with extensions 38 at its inner end to fit the inward extensions of the groove 34. Moreover the grooves 34 are provided with suitable wearing plates 39 to take up the wear of the moving abutment 35.

One of the stator halves is provided with a steam port 40 and from this steam port 40 leads a steam pipe 41. This steam pipe 41 is connected to a valve casing 42 wherein is mounted a valve 43 having a port 44 extending transversely therethrough. The valve 43 is likewise provided with a stem 45 upon which is secured a gear 46. Meshing with this gear 46 is a rack bar 47 mounted in suitable guides in a frame 48 carried on the upper side of the stator. This rack bar is normally urged upward by the action of a coil spring 49 which is secured to the frame and bears against the lower end of said rack bar. The upper end of this rack bar is connected to one end of a lever 50 which is pivoted intermediate its ends to the frame 48 and the other end of this lever 50 is engaged by a rod 51 which is in turn connected to an eccentric rod 52 having its lower end connected to an eccentric strap 53 surrounding an eccentric 54 keyed to the shaft 18. The stator is likewise provided with an exhaust port 55 from which leads a suitable exhaust pipe 56. The rod 51 moves through a guide 57 on the frame 48.

In the operation of the device steam is admitted between the piston 32 and abutment 35 through the port 40. This drives the rotor around and when the rotor arrives at the proper position the slanting forward sides 33 of the piston 32 engages the lower or inner edge of the abutment 35 and cause 45 this abutment to rise against the action of the spring 37'. Just prior to this time the piston has uncovered the exhaust port 55 and the exhaust steam escapes therefrom. As the piston moves past the abutment the

latter drops on the descending or rear side 50 of said piston and steam is again admitted between the piston and abutment thus causing a continuous rotation. It is to be noted that the steam is cut off from time to time by the action of the eccentric, the eccentric 54 causing the eccentric rod 52, and consequently the rod 51 to reciprocate which in turn causes the lever 50 to operate and this, through the action of the rack 47 and gear 46 oscillates the valve 43 and consequently 60 opens and closes the steam pipe. It is obvious that suitable oil cups may be supplied to any of the friction surfaces of the device but these have not been deemed necessary here to be shown as they form no particular 65 part of the invention and are common in all engines where two surfaces come together, one of which is a moving surface.

There has thus been provided a simple and efficient device of the kind described and 70 of the character specified.

It will be obvious that many minor changes may be made in the form and construction of this invention without departing from the material principles thereof. It 75 is not therefore desired to confine the invention to the exact form herein shown and described, but it is wished to include all such as come properly within the scope claimed.

Having thus described the invention, what 80 is claimed as new, is:—

The combination with a rotary engine provided with a shaft; of means to intermittently supply steam to said engine comprising an eccentric mounted on said shaft, a 85 strap surrounding said eccentric, a reciprocable rod connected to said strap, a steam supply pipe having an oscillatory valve, a gear connected to said valve, a rack engaging said gear, and means to connect the rack 90 and reciprocable rod.

In testimony whereof, I affix my signature, in the presence of two witnesses.

GEORGE BOLTZ.
